E. KNÜSLI.
FLUSHING DEVICE WITH AIR-TIGHT VESSELS FOR WATER CLOSETS.
APPLICATION FILED SEPT. 11, 1917.

1,293,121.

Patented Feb. 4, 1919.

UNITED STATES PATENT OFFICE.

EMILE KNÜSLI, OF ZURICH, SWITZERLAND, ASSIGNOR TO THE FIRM OF PITO A.-G., OF ZURICH, SWITZERLAND.

FLUSHING DEVICE WITH AIR-TIGHT VESSELS FOR WATER-CLOSETS.

1,293,121.

Specification of Letters Patent.

Patented Feb. 4, 1919.

Application filed September 11, 1917. Serial No. 190,798.

To all whom it may concern:

Be it known that I, EMILE KNÜSLI, civ. engineer, a citizen of the Swiss Confederation, residing at Badenerstrasse No. 440, 5 Zurich, Switzerland, have invented new and useful Improvements in Flushing Devices with Air-Tight Vessels for Water-Closets, of which the following is a specification.

The present invention relates to a flushing device with an air-tight vessel for water closets and more particularly, to that class of flushing device in which a valve, interconnecting the air-tight vessel with the main, is opened by pushing or pulling a 15 knob. When the pressure in the air-tight vessel attains a certain value, the water exit of the vessel is automatically opened by the action of the pressure on a stepped piston in such a manner that, when the inflow of 20 water into said vessel has been stopped by closing the main valve, the vessel is brought into connection with the flushing pipe.

The primary object of the present invention is the provision of a flushing device of 25 the said class in which the construction and arrangement of the water inflow and outflow valves, and of the air-tight vessel, is modified and simplified insuring the automatic action of the flushing device under any condition.

With the foregoing and other objects in view, which objects will appear as the description proceeds, the invention will be found to reside in the combination and arrangement of parts, and in the details of construction hereinafter described and claimed. 35 It will be understood that changes in the precise embodiment of the invention herein disclosed can be made without departing 40 from the scope of the invention.

In the drawings:

Figures 1 and 2 show a flushing device in sectional elevation, the piston being shown in two different positions.

The flushing device comprises a cylindrical air-tight vessel 1 which may be made of suitable sheet metal. This vessel is provided at its ends with sockets 20 and 21, respectively. A valve case 2 is screwed 45 into the upper socket 21, and is provided with a branch 3 by means of which the flushing device is connected to a water main in any suitable manner, not shown in the drawings. In the casing 2, two rings 5 of 50 flexible packing material are co-axially ar-

ranged and are held in position by two rings 23 and 24 screwed in the casing 2. The orifice of the branch 3 is situated between the rings 5 which rings, coacting with the piston 4, serve to govern the outflow of 60 water from the main. The piston 4, which is a stepped piston, is provided with a lower part 25 and an upper part 12, the diameter of the upper part, which is provided with a neck 6, being slightly larger than that of 65 the lower part 25.

The piston 4 which is hollow, is open at the top and bottom and is rigidly connected to a stem 7 of a knob 9 thus serving as a handle by which it may be manipulated.

The stem 7 which is slidably arranged in a cap 8 of the casing 2 is hollow and communicates with the interior of the piston 4 by means of holes. The knob 9 is provided with holes 10 by means of which the air-tight vessel communicates with the atmosphere. This knob is screwed on the stem 7 and the piston 4 rests, by means of the knob 9, on the cap 8. The lowest possible position which the piston 4 may assume (see Fig. 1) 80 depends on the position of the knob 9 and the stem 7. The latter is further provided with a collar 11 which strikes against the cap 8 when the piston moves upward thereby limiting the upward movement of the 85 piston 4.

At the lower end of the vessel 1, in the socket 20, a valve case 22 is arranged in which a ring 16 of flexible packing material is held by means of a ring 27 screwed into 90 said casing. The rings 16 coacting with the lower end of the piston 4 serve as an outflow valve for the air-tight vessel. In the socket 20 a guide 17 is provided for the lower end of the piston 4 which guide consists of a 95 piece of tube, tapering at the upper end and fixed with the lower end in a slotted disk 29 screwed into the casing 22. On the socket 20 the flushing pipe 15 leading to the water closet is fixed in the well-known manner.

The action of the flushing device is as follows:

When at rest, the piston 4 is in the position shown in Fig. 2 and the air-tight vessel 1 is open at the bottom and free of water. 105 If, then the knob 9 is pushed down until it abuts on the cap 8 the water flows from branch 3 into the vessel 1 and the restricted portion 6 of the piston 4 forms a passage for the water around the ring 5. The piston 110

4 remains in the assumed position, in view of its weight until the pressure in the vessel has attained a certain value which is sufficient to overcome the resistance. It then 5 opposes the upward movement of the piston 4 and lifts the latter by the excess of pressure on the surface of the upper larger part 12 of the piston 4.

The piston 4 in rising closes the connection 10 between the vessel 1 and the branch 3 and immediately thereafter opens the outflow opening at the bottom of the vessel. The water issues under pressure and no loss of energy occurs as no deviation of the issuing 15 water takes place. After the given quantity of water has finished flowing, the flushing device remains in the position formally described, the vessel 1 being at all times empty. Leak water which may pass 20 along the ring 5 flows off through holes 14 either inside or outside of the piston.

It is evident that various changes may be made in the form and arrangement of parts but what I claim as new and wish to secure 25 by Letters Patent is:

1. A flushing device for water closets including a tank, an inlet opening at the upper end of the tank, and an outlet at the bottom of the tank, valves provided for each 30 of said openings of which the lower is normally open and the upper one closed, and means for actuating said valves whereby to close the outlet and open the inlet valves, and further means for automatically closing 35 the inlet and opening the outlet valve when the tank is nearly filled with water.

2. A flushing device for water closets including a tank, an inlet opening at the upper end of the tank, and an outlet at the bottom of the tank, valves provided for each 40 of said openings of which the lower is normally open and the upper one closed, and means for actuating said valves whereby to close the outlet and open the inlet valves, such means including a single valve stem 45 extending through the tank and projecting beyond the outer end of the same and terminating at this end in an operating handle, and further means for automatically closing the inlet and opening the outlet valves when 50 the tank is nearly filled.

3. A flushing device for water closets including a tank, an inlet opening at the upper end of the tank and an outlet at the bottom of the tank, valves provided for 55 each of said openings of which the lower is normally open and the upper one closed, and means for actuating said valves whereby to close the outlet and open the inlet valves whereby to permit water to rise in said 60 tank, the upper of said valves being provided with an enlarged valve stem above the valve, against which enlarged portion the pressure will be exerted, which pressure is transmitted to confined air within said 65 tank by the rising water therein, whereby to move the valve stem to close the inlet and open the outlet valves when the tank is nearly filled.

In testimony whereof I affix my signature. 70

EMILE KNÜSLI.
